(57) **CLAIM**

The ornamental design for a handheld current sensor as shown and described.

DESCRIPTION

FIG. 1 is a perspective view of a first embodiment of a handheld current sensor according to the present invention, wherein the shaded portions indicate a first material and the unshaded portions indicate a second material;

FIG. 2 is a front elevation view of the embodiment of FIG. 1;

FIG. 3 is a rear elevation view of the embodiment of FIG. 1;

FIG. 4 is a left side elevation view of the embodiment of FIG. 1;

FIG. 5 is a right side elevation view of the embodiment of FIG. 1;

FIG. 6 is a top plan view of the embodiment of FIG. 1;

FIG. 7 is a bottom plan view of the embodiment of FIG. 1;

FIG. 8 is a cross-section view of the embodiment of FIG. 1, taken along line 8-8 of FIG. 2;

FIG. 9 is a perspective view of a second embodiment of a handheld current sensor according to the present invention;

FIG. 10 is a front elevation view of the embodiment of FIG. 9;

FIG. 11 is a rear elevation view of the embodiment of FIG. 9;

FIG. 12 is a left side elevation view of the embodiment of FIG. 9;

FIG. 13 is a right side elevation view of the embodiment of FIG. 9;

FIG. 14 is a top plan view of the embodiment of FIG. 9;

FIG. 15 is a bottom plan view of the embodiment of FIG. 9;

FIG. 16 is a cross-section view of the embodiment of FIG. 9, taken along line 16-16 of FIG. 10;

FIG. 17 is a perspective view of a third embodiment of a handheld current sensor according to the present invention;

FIG. 18 is a front elevation view of the embodiment of FIG. 17, wherein rear elevation, left side, and right side views are omitted as being identical to the front elevation view;

(Continued)

FIG. 19 is a top plan view of the embodiment of FIG. 17;
 FIG. 20 is a bottom plan view of the embodiment of FIG. 17;
 and,
 FIG. 21 is a cross-section view of the embodiment of FIG. 17, taken along line 21-21 of FIG. 18.
 Elements shown in broken lines are for illustrative purposes only and form no part of the claimed design.
